Primary Examiner — Adam C Mager

(57)

CLAIM

The ornamental design for an automobile as shown and described.

DESCRIPTION

1. Automobile

1.1 : Perspective

1.2 : Front

1.3 : Back

1.4 : Right

1.5 : Left

1.6 : Top

Fig. 1.1 is a perspective view; fig. 1.2 is a front view; fig. 1.3 is a rear view; fig. 1.4 is a right side view; fig. 1.5 is a left side view; fig. 1.6 is a top view.

The broken lines in the reproductions are for illustrating portions of the automobile that form no part of the claimed design.

1 Claim, 6 Drawing Sheets
